YARN TENSIONING DEVICE

James R. O'Dell, Kingsport, Tenn., assignor to
Eastman Kodak Company, Rochester, N. Y., a
corporation of New Jersey

Application June 14, 1949, Serial No. 99,037

15 Claims. (Cl. 242—45)

1

The present invention relates to yarn winding machines, and more particularly to a new and improved yarn tensioning device therefor.

The device of the present invention imparts tension to the moving yarn as it is being wound into a package or cone on a winding machine. The coning operation, in general, is one wherein the yarn is taken from a package, such as a bobbin, cake, spool, etc., up through a guide or series of guides, a variable tensioning device, and automatic spindle stopping mechanism, over a traversing guide onto a tube. As the amount of yarn increases on the cone or tube, the tension placed on the yarn by the variable tensioning device decreases, the amount of tension and rate of decrease being controlled by adjustment of a system of levers and a cam connecting the tensioning device to the traverse guide mechanism.

Up to the present time, the most common type of tensioning device manufactured for general use on a winding machine is one composed of a pair of intermeshing fingers or rungs, one side being fixed while the other is free to move in such a manner that gradations of tension are placed on yarn passing between the two parts of the device by increasing or decreasing the degree of intermeshing of the fingers. This type of tensioning device is known as a "washboard" type. One difficulty with this type of tensioning control is that it sometimes is thrown open due to momentary applications of more than normal withdrawal tension from the supply package. Since no fixed restraining device can be placed on the mobile part of the device to restrict its movement to a very small degree and yet obtain decrease in the amount of tension applied, there then occurs a very short period of time when insufficient tension is applied to the yarn to keep it under positive control. This causes small amounts of yarn to be wound up loosely on the cone which results often in tangles and loops which may be broken by the traverse guide. Also, any unevenness in the supply package causes considerable "chatter" of the "washboard" tension control, resulting in variations of tension applied to the yarn.

In order to overcome these difficulties, the present invention provides a new and improved tensioning device which serves to pinch the yarn as it passes in a straight line through the tensioning device. The latter comprises a fixed flat plate, and a pivoted or movable bowed or arced plate which presses against the rigid plate with any predetermined and variable force to apply

2

pressure to the yarn to tension the latter. As the yarn is being wound, the pressure applied by the tensioning device will decrease gradually and in timed relation to the winding operation so as to insure the application of the proper tension by the tensioning device. The operation of the present tensioning device is smooth, gradual, without forcing the yarn to deviate from a straight line while passing between the yarn tension plates. The arced or bowed plate may be easily and readily cleaned or replaced.

The invention has as its principal object the provision of a yarn tensioning device which eliminates chattering or tendency to be thrown open by sudden applications of tension below the tensioning device.

A further object of the invention is the provision of a tensioning device which applies required tension to the yarn by applying a pinching pressure thereto without forcing the yarn to deviate from a straight path while passing through the tensioning device.

Yet another object of the invention is the provision of a yarn tensioning device which automatically distributes evenly the applied pressure upon the yarn regardless of which area of the gate the yarn passes through.

Still another object of the invention is the provision of a yarn tensioning device which can be readily and easily cleaned, applied to existing machines without material alteration thereof, and obtains the desired gradations in tension.

And a further object of the invention is the provision of a yarn tensioning device in which the tension applied to the yarn is independent of the tensile properties of the material used in the device.

To these and other ends, the invention resides in certain improvements and combinations of parts, all as will be hereinafter more fully described, the novel features being pointed out in the claims at the end of the specification.

In the drawings:

Fig. 1 is a side elevation view of one unit of a yarn winding machine, showing the relation thereto of a yarn tensioning device constructed in accordance with the present invention;

Fig. 2 is a plan view of the tensioning device of the present invention and a part of the operating mechanism thereof, on a larger scale than Fig. 1, showing the arrangement of parts;

Fig. 3 is a perspective view of the tensioning device per se, showing the relation of the parts and the double pivoting arrangement of the

bowed plate to insure uniform pressure on the yarn and to facilitate cleaning of the parts;

Fig. 4 is a perspective view taken from the opposite side of the tensioning device from that illustrated in Fig. 3, showing the arrangement of the operating linkage to the tensioning device, and with the device adjusted for the low tension required near the end of the winding operations; and

Fig. 5 is a view similar to Fig. 4, but showing the linkage adjusted to provide a higher tension, such as required near the beginning of the winding operation.

Similar reference numerals throughout the various views indicate the same parts.

In Fig. 1, a supply package 11 is shown from which the yarn 12 is being drawn through a guide 13, and then through the tensioning device of the present invention, generally indicated by the numeral 14, and hereafter more fully described. From the tensioning device, the yarn passes through a cleaner 15, through a spindle stopping mechanism 16 and from there through a traverse guide 17 to a cone 18 which is being wound on a tube 19 carried by a spindle 20 rotating at a constant speed. The guide 17 is held firmly against cone 18 by a counterweight 21, the connecting arm 22 being pivoted at 23. With the exception of the tensioning device 14, the above-described structure is of a standard or well known construction and forms no part of the present invention. Accordingly, further details are not deemed necessary to those skilled in the art, or to provide a clear understanding of the present invention.

The tensioning device of the present invention is secured to the machine frame 26 by a bracket 27, as best shown in Fig. 2. A vertical fixed flat steel plate 28 is fastened to the bracket 27 by any suitable means, for example, a screw 29. A movable frame 30 is rockably or pivotally supported on a rod 31, the ends of which are anchored in spaced lugs or bosses 32 formed on bracket 27. Thus, the frame 30 is free to swing on the bracket 27 about the vertical axis formed by rod 31. The frame 30 is formed with a pair of spaced arms 33 which overlie plate 28, as best shown in Fig. 3. The free ends of arms 33 are formed with spaced lugs 34 to receive a pin 35 on which is mounted a pair of spaced ears 36 formed from and extending rearwardly from a hanger frame or holder 37, as clearly illustrated in Fig. 3. The frame 37 is preferably cut away to provide an open rectangular frame, as shown in Fig. 3. The top and bottom edges 38 and 39 respectively of the frame 37 are bent to form lugs or channels 40 adapted to receive slidably and detachably a thin steel plate 41. The latter is preferably constructed of spring steel of approximately 0.005 in., in thickness and has a length slightly greater than the vertical distance between the lugs 40 so that when the top and bottom edges of the plate 41 are inserted in position in the lugs 40, the plate will be bowed or arched toward the fixed plate 28, as shown in the drawings. The side of the fixed plate 28 toward the bowed plate is preferably chrome-plated.

The bowed plate 41 is positioned adjacent the fixed plate 28 and co-operates therewith to pinch the yarn 12 as it passes between the plates to apply the desired tension to the yarn without causing the latter to deviate from a straight line while passing between the plates, the advantages of which are deemed apparent to those familiar with such tensioning devices.

It will be apparent from the above description and the drawings, that the bowed plate 41 and its supporting hanger frame 37 have a dual movement. They may rock about pin 35 relative to the movable frame 30, and may also move as a unit with the latter about the axis of rod 31. Thus, the bowed plate 41 is movable about two spaced parallel vertical axes. Such an arrangement assures proper contact of the bowed plate 41 with the fixed plate 28 with the pressure evenly distributed across the entire width of the contact area between the plates. This mounting of the bowed plate also enables the latter to be moved toward and away from the fixed plate to vary the area of contact, and also to enable the bowed plate to be turned inside out for ready cleaning or replacement, if desired.

The tension imparted to the yarn by the tension device of the present invention, Fig. 3, is determined by the pressure applied to the yarn by the plates 28 and 41. For reasons to be later more fully described, it is desirable that this applied or additive tension be gradually decreased as the yarn is being wound. To secure this result, the frame 30, and hence the bowed plate 41, is connected by a linkage system, of well known construction, to the cone 18 so that the position of the plate 41 is controlled from the cone 18. With this arrangement, the bowed plate 41 is gradually moved away from the fixed plate 28 so as to reduce progressively the tension applied to the yarn by the tensioning device of the present invention. However, due to the flexible nature of plate 41, it always remains, during the winding of the cone, in contact with plate 28, while the area of contact between the plates varies in direct proportion to the force applied through the linkage system. The latter is of old construction and does not form a part of the present invention, but is illustrated and described so that the operative forces which actuate and control the tensioning device will be fully understood.

This linkage has a differential arm or lever 45 pivoted at its upper end to the machine frame so that the lower end of the lever may swing in an arc, as is apparent from an inspection of Figs. 4 and 5. The lower end of this lever is provided with a shaft 46 adapted to receive loosely a pair of spaced ears or bearings 47 formed on a differential arm or member 48 having a laterally-extending arm 49 carrying a weight 50 spaced from the shaft 46, as best shown in Figs. 4 and 5. It is apparent from an inspection of these figures that the weight 50 is eccentrically mounted on the arm 49 relative to the shaft 46; and, if the arm 49 were free, the weight 50 would rotate or turn the arm 49 in a clockwise direction about the shaft 46 until the arm extends vertically downwardly so that it will be suspended from shaft 46.

The member 48 is provided with a laterally-projecting portion 51 extending substantially at right angles to arm 49, as best shown in Figs. 4 and 5. The free end of portion 51 is formed with an elongated slot 52 adapted to receive slidably a link 53 of the shape best shown in Figs. 4 and 5. The ends of link 53 are received loosely in holes formed in the ends of arms 60 forming parts of the flanges of the channel-shaped frame 30 and extending substantially at right angles to arms 33. Thus, the eccentric weight 50 is connected to the frame 30, and hence to the bowed plate 41 for a purpose to be later described.

From an inspection of Figs. 4 and 5, it will be

apparent that if a leftward force is applied to link 53, this force will tend to rotate frame 30 in a clockwise direction about rod 31 to move frame 37 and bowed plate 41 towards the fixed plate 28 to pinch the yarn 12 therebetween to apply tension to the yarn. On the other hand, a rightward force applied to the link 53 will tend to rotate frame 30 in a counterclockwise direction about rod 31 to move the bowed plate 41 away from the fixed plate 28 to reduce the pinching action of the yarn to reduce the tension thereof. It is also apparent from an inspection of Figs. 4 and 5 that the weight 50 is connected to the link 53 by reason of arm 49, member 48 and portion 51. Also, when the weight is moved from the position shown in Fig. 5 to that shown in Fig. 4, the eccentricity of the weight relative to shaft 46 is reduced. As the eccentricity is reduced, the weight will apply less force on the link 53 and hence on the bowed plate 41. Thus, the weight 50 is angularly displaceable, and the degree of displacement thereof will determine the force transmitted to the bowed plate 41 to thus control or regulate the yarn tension, as will be later more fully discussed.

As is well known, and as briefly mentioned above, as the cone 18 increases in size, the withdrawal tension of the yarn increases. Therefore, in order to provide an even tension throughout the length of the yarn on the cone, the tension applied to the yarn by the tensioning device 14 must gradually decrease as the withdrawal tension increases or as the cone builds up. Thus, the tension applied by the plates 28 and 41 must be gradually and evenly reduced as the yarn cone increases in diameter. In order to secure this result, the arm 49 is connected to the traverse guide 17 so that as the latter moves to the right, see Fig. 1, during the building up of the cone, the arm 49 will be rocked in a clockwise direction about shaft 46 to decrease the eccentricity or angular displacement of the weight 50 relative to shaft 46 to reduce thereby the effect of the weight on the link 53 and hence on the frames 30 and 37 and the bowed plate 41 to diminish the pinching force applied to the plates 28 and 41 thereby to decrease the yarn tension the proper amount and in a proper timed relation to the building up of the cone, the advantages of which are deemed apparent. As the effect of the weight 50 is reduced, the pressure applied to plate 41 is reduced and the latter changes its shape and becomes more bowed, thus decreasing the area of contact between the plates 28 and 41. As the plate 41 becomes more bowed, it reacts on the fixed plate 28 to move the plate 41 and the frames 37 and 30 away slightly from the plate 28 so as to reduce the pinching effect on the yarn to diminish the tension applied or added by the tensioning device of the present invention.

In order that the angular displacement of weight 50 will be in proper amount and in proper proportion, the displacement is controlled from and by the cone 18. To secure this result, a cam 55, of the shape shown in Figs. 4 and 5, is loosely mounted on a stud 56, secured in machine frame 26, see Fig. 2. The cam 55 is provided with a radial crank 57, the free end of which is pivotally connected at 58 to the right end of a link 59, the left end of which is connected to the counterweight 21, see Fig. 1.

At the beginning of the winding operation, cone 18 is small and the traverse guide 17 is moved to its extreme leftward position, which is to the left of that shown in Fig. 1, as is ap-

parent. In this leftward position, the arm 22 has been rocked about the pivot 23 to move the counterweight 21 to its rightward position. Such movement of the counterweight causes the link 59 to rock crank 57 and cam 55 in counterclockwise direction to the position shown in Fig. 5. Such rotation of the cam causes the latter to engage and rock lever 45 in a clockwise direction about its pivot. Such movement also serves to carry member 48, arm 49, weight 50 and portion 51 to the left, as viewed in Fig. 5. However, as portion 51 is secured slidably to the link 53, the leftward movement of member 48 serves to rock the latter counterclockwise on shaft 46 to move or displace the arm 49 and weight 50 through an angle A to the position shown in Fig. 5. This is the position of the parts near the beginning of the winding operation, and, in this position, the eccentricity or displacement of the weight 50 exerts a leftward force on link 53, and this force is transmitted through frames 30 and 37 to press the bowed plate 41 towards plate 28 with the maximum force to apply the maximum tension to the yarn.

The diminishing of the amount of tension from start to finish of the cone is of paramount importance to the constant spindle speed obtained, since the yarn take-up speed increases as the diameter of the cone increases. As the take-up speed increases, also there is a corresponding increase in withdrawal tension. To compensate for this increase in withdrawal tension, there must be an automatic and gradual decrease of pressure applied mechanically to the yarn so there will be a more or less uniform amount of tension applied to the yarn. Only in this manner can straight, well-shaped cones of high quality be obtained.

As the cone 18 increases in size, the traverse guide 17 rocks to the right about pivot 23 to move the counterweight 21 to the left or in the direction of the arrow, Fig. 1. This leftward movement of the counterweight exerts a leftward pull on link 59 to rock cam 55 gradually in a clockwise direction towards the position illustrated in Fig. 4. As the cam is thus rotated, the eccentricity or angular displacement of the weight 50 exerts a downward pull to hold the lever 45 always in contact with the cam 55. The result is that the lever 45 gradually moves in a counterclockwise direction about its pivot, and carries member 48, arm 49, weight 50 and the portion 51 to the right. This rightward movement causes portion 51 to slide vertically along link 53 to rotate member 48 in a clockwise direction about shaft 46. Such rotation will gradually move arm 49 and weight 50 to the position shown in Fig. 4 to form a smaller angle A' which is smaller than angle A, Fig. 5. By thus reducing the angle, the angular displacement or eccentricity of the weight 50 relative to the shaft 46 is correspondingly reduced, and this reduced displacement gradually decreases the leftward force applied to link 53 and hence the leftward force applied to the bowed plate 41. As the force of the latter is reduced, it will pinch the yarn less to impart a reduced tension thereto.

It will be understood, of course, that the movement of the parts from the position shown in Fig. 5 to that shown in Fig. 4 is gradual and in direct proportion to and in time relation with the winding of the yarn on the cone. Accordingly, the pressure exerted by the plate 41 is gradually reduced to decrease the yarn tension uniformly and continuously during the winding, and

this decrease is sufficient to compensate for the withdrawal tension due to the pulling off of the yarn so as to insure a uniform tension throughout the length of the yarn on the cone 18. The amount of angular displacement of the weight 50 determines what horizontal vector of force is exerted against link 53 and hence by plate 41 against the yarn. Thus, the force exerted on link 53 by the weight 50 is transmitted through frames 30 and 31 to the bowed plate 41. As the frame 31 is free to pivot on pin 35, the force holding the plates 28 and 41 together will permit perfect alignment of the plates with a uniform pressure across the width of the contact area and while the yarn is passing in a straight line between the plates. It will be noted that the connection between the portion 51 and link 53 performs two functions; first, it serves to transmit the force of the displaced weight 50 to the bowed plate 41 to control tension; second it serves to rock the member 43 and arm 49 to displace weight 50 when the cam 55 rocks lever 45. As the force on plate 41 is reduced, the latter becomes more bowed, thus reducing the area of contact with plate 28 to decrease the pinching effect of the plate to diminish the tension applied to the yarn by the plates.

From the above description, it is apparent that the present invention provides a yarn tensioning device which applies tension to the yarn without forcing the yarn to deviate from a straight line or path through the tensioning device. In addition, the device applies a gradual decrease in tension to compensate for gradual increase in withdrawal or pull-off tension to insure a uniform tension throughout the yarn package. This variation in tension at the tensioning device or gate is secured by an angular displaceable weight, the angular relation of which is varied during winding to produce a gradual decrease in pressure or force at the gate parts. The tensioning device automatically distributes evenly the applied pressure upon the yarn regardless of the area of the gate through which the yarn passes. The frame 31 may be readily, easily and quickly swung about pin 35 to turn the bowed plate inside out for a thorough cleaning without changing the degree of tension exerted by the device. Also, the bowed plate can be quickly replaced merely by sliding it out of the lugs or channels 40 and sliding a new plate 41 into position. The tensioning device or gate can be applied to existing machines. The variation in yarn tension at the gate is secured by means of the angular displaceable weight and is independent of tensile properties of the material used for the gate parts.

While one embodiment of the invention has been disclosed, it is to be understood that the inventive idea may be carried out in a number of ways. This application is, therefore, not to be limited to the precise details disclosed, but is intended to cover all variations and modifications thereof falling within the scope of the appended claims.

What I claim is:

1. A yarn tensioning device comprising, in combination, a fixed flat plate, a bowed plate co-operating with said fixed plate to pinch the yarn to apply tension thereto, and means for rockably mounting said bowed plate for freedom of movement about axes parallel to the yarn to permit unrestricted adjustment of the latter so as to align with said fixed plate to provide uniform pressure across the area of contact of said plates.

2. A yarn tensioning device comprising, in combination, a fixed flat plate, a bowed plate co-operating with said fixed plate to pinch said yarn therebetween to apply tension thereto, a holder for said bowed plate means for mounting said holder for movement about a pair of parallel axes, and means on said holder for maintaining said second plate in a bowed relation.

3. A yarn tensioning device comprising, in combination, a fixed flat plate, a second plate bowed toward said fixed plate and co-operating therewith to pinch the yarn therebetween to apply tension thereto, a holder for said bowed plate, and a pair of lugs formed on said holder and adapted to receive slidably opposite edges of said second plate, said lugs being spaced a distance less than the width of said plate so as to bow the latter toward said fixed plate when said edges are inserted in said lugs.

4. A yarn tensioning device comprising, in combination, a fixed flat plate, a second plate bowed toward said fixed plate and co-operating therewith to pinch the yarn therebetween to apply tension thereto, a holder for said bowed plate, a pair of lugs formed on said holder and adapted to receive slidably opposite edges of said second plate, said lugs being spaced a distance less than the width of said plate so as to bow the latter toward said fixed plate when said edges are inserted in said lugs, and means for pivotally mounting said holder for free movement to permit automatic adjustment of said bowed plate to permit alignment of said plates to insure uniform pressure across the full area of contact between said plates.

5. A yarn tensioning device comprising, in combination, a support, a fixed flat plate carried by said support, a holder, a second plate removably and slidably positioned on said holder, means on said holder for bowing said second plate about an axis and toward said fixed plate so as to co-operate therewith to pinch the yarn therebetween to apply tension thereto, and means for rockably mounting said holder on said support about axes normal to said first axis to provide freedom of movement to said holder to permit perfect alignment of said plates with uniform pressure across the width of the area of contact between said plates.

6. A yarn tensioning device comprising, in combination, a fixed flat plate, a holder, a thin flexible plate slidably positioned on said holder, means on said holder for detachably securing said second plate thereon, said means being spaced a distance less than the width of said plate so as to bow the latter about an axis and toward said fixed plate to co-operate therewith to pinch the yarn therebetween to apply tension thereto, and a pivot for said holder arranged normal to the axis of bowing of said second plate so as to permit freedom of movement of said holder and said second plate to permit perfect alignment of said plates with uniform pressure across the width of the area of contact between said plates.

7. A yarn tensioning device comprising, in combination, a fixed flat plate, a pivoted frame, a holder arranged adjacent and substantially parallel to said fixed plate, a bowed plate carried by said holder and co-operating with and pressing against said fixed plate to pinch the yarn therebetween to apply tension thereto, and means for rockably mounting said holder on said frame to permit said bowed plate to align with said fixed plate to insure a uniform pressure

across the area of contact between said plates, said holder being adjustable toward and away from said fixed plate to vary the pressure of said bowed plate against said fixed plate to alter the tension applied by said device.

8. A yarn tensioning device comprising, in combination, a fixed flat plate, a pivoted frame, a holder arranged adjacent and substantially parallel to said fixed plate, a thin flexible plate, means on said holder both for securing said second plate detachably thereto, and for bowing said second plate toward said first plate to press thereagainst and to co-operate therewith to pinch the yarn therebetween to apply tension thereto, and means for pivotally mounting said holder on said frame for movement relative thereto to permit said bowed plate to align with said fixed plate to provide a uniform pressure across the area of contact between said plates, said holder being adjustable toward and away from said fixed plate to vary the pressure of said bowed plate against said fixed plate to alter the tension applied by said device.

9. A yarn tensioning device comprising, in combination, a support, a fixed flat plate carried by said support, a frame pivoted on said support, a holder arranged adjacent said fixed plate, a thin flexible plate, means for slidably mounting said second plate on said holder, means on said holder for bowing said second plate toward said fixed plate to contact the latter and to co-operate therewith to pinch the yarn therebetween to apply tension thereto, and means for rockably mounting said holder on said frame to permit movement of said holder relative to said frame to allow said bowed plate to be adjusted automatically in alignment with said fixed plate to provide uniform pressure across the width of the contact area between said plates, the pinching action of said plates being adjustable to vary the tension applied to the yarn.

10. A yarn tensioning device comprising in combination, a support, a vertical fixed flat plate carried by said support, a frame, means for pivoting said frame about a vertical axis on said support, a vertically arranged holder positioned adjacent said fixed plate, a thin flexible plate, means for slidably securing said flexible plate on said holder and for bowing said flexible plate toward said fixed plate about a horizontal axis and to press against the fixed plate to co-operate therewith to pinch the yarn therebetween to apply tension thereto, and means for pivoting said holder on said frame about an axis parallel to the pivot of said frame to permit said holder to rock relative to said frame to align the bowed plate with the fixed plate to provide uniform pressure across the width of the contact area of said plates, the bowing of said flexible plate being variable to change the tension applied to said yarn by said device.

11. A yarn tensioning device comprising, in combination, a support, a vertical fixed flat plate carried by said support, a frame, means for pivoting said frame about a vertical axis on said support, a vertically arranged holder positioned adjacent said fixed plate, a thin flexible plate, vertically spaced channels on the side of said holder toward said fixed plate to receive slidably opposite edges of said thin plates to secure the latter detachably to said holder, said channels being spaced a distance less than the height of said thin plate to bow the latter toward said fixed plate and in the pressing contact with the latter and co-operate therewith to pinch the

yarn therebetween to apply tension thereto, and a vertical pin carried by said frame but spaced from the pivot thereof to mount said holder rockably on said frame for movement relative thereto to align said bowed plate with said fixed plate to insure uniform pressure across the width of the area of contact of said plates, the bowing of said flexible plate being adjustable to change the pinching pressure applied to yarn to alter the applied tension.

12. A yarn tensioning device comprising, in combination, a support, a vertically arranged flat plate fixedly mounted on said support, a vertically arranged channel shaped frame, a vertical rod extending through the opposite flanges of said frame to mount said frame pivotally on said support, a flat vertical holder positioned adjacent said fixed plate, a thin flexible plate, vertically spaced lugs formed on said holders on the side thereof toward said fixed plate to receive slidably opposite edges of said thin plate, said lugs being spaced a vertical distance less than the height of said thin plate so as to bow the latter toward said fixed plate and into pressing contact with the latter and cooperating therewith to pinch the yarn therebetween to apply tension thereto, and a pin carried by the web of said frame for rockably mounting said holder thereto to allow the holder to rock relative to said frame to align said bowed plate with said fixed plate to insure uniform pressure across the width of the area of contact of said plates, the pivoting of the frame on the support and the holder on the frame permitting the holder to move with the frame and also relative thereto to open the device widely to permit easy cleaning of the plates, said holder being adjustable to vary the bowing of said flexible plate to change the pressure applied to said flexible plate to alter the tension imparted to said yarn by said device.

13. A yarn tensioning device for use on a yarn winding machine in which the yarn is pulled from a package with an increasing tension and wound up on a cone, said device being positioned between said package and cone and comprising a fixed flat plate, a holder positioned adjacent said plate, a thin flexible plate, means on said holder engaging opposite edges of said flexible plate to connect the latter detachably to said holder and to bow said flexible plate toward said fixed plate so as to press against the latter and to co-operate therewith to pinch the yarn as it passes in a straight line between said plates to apply an additive tension to said yarn independent of the pull-off tension, and means for mounting said holder for movement about a pair of independent axes, movement about one of said axes permitting said flexible plate to be aligned automatically with said fixed plate to provide a uniform pressure across the area of contact between said plates, said holder being adjustable about the other axis as the yarn is being wound to change the pressure of said flexible plate against the fixed plate to decrease gradually the tension applied by the device to the yarn to compensate for the increasing pull-off tension to provide a substantially constant tension yarn at said spool.

14. A yarn tensioning device for use on a yarn winding machine in which the yarn is pulled from a package with an increasing tension and wound up on a cone, said device being positioned between said package and cone and comprising, a fixed plate, a holder positioned adjacent said plate, a thin flexible plate, means on said holder engaging opposite edges of said flexible plate to

11

connect the latter detachably to said holder and to bow said flexible plate toward said fixed plate so as to press against the latter and to co-operate therewith to pinch the yarn as it passes in a straight line between said plates to apply an additive tension to said yarn independent of the pull-off tension, a frame, means for rockably mounting said holder on said frame for adjustment relative thereto, and means for rockably mounting said frame independently of said first mounting, said first mounting permitting said holder and flexible plate to be adjusted automatically to align the flexible plate with the fixed plate to permit alignment of said plates to provide a uniform pressure across the width of the area of contact between said plates, said second mounting serving to permit said holder and flexible plate to move in a direction normal to said fixed plate to alter the area of contact between said plates during winding to change the tension applied to 20 said yarn in accordance with the pull-off tension to deliver a substantially constant tension yarn at said spool.

15. A yarn tensioning device for use on a yarn winding machine in which the yarn is pulled 25 from a package with an increasing tension and wound up on a cone, said device being positioned between said package and cone and comprising, a fixed flat plate, a flat holder positioned adjacent said plate, a thin flexible plate, spaced lugs 30 formed on the side of said holder toward said fixed plate for receiving opposite edges of the latter to connect it detachably on said holder, said lugs being spaced a distance apart less than the height of said flexible plate so that when said 35 latter plate is connected to said holder it will be

5
10
15

bowed about an axis and toward said fixed plate to engage the latter over an area and to co-operate with said fixed plate to apply an additive tension to said yarn independently of the pull-off tension, an adjustable frame, means for rockably mounting said holder on said frame about an axis normal to the axis of bowing of said flexible plate, said means enabling said flexible plate to align automatically with said fixed plate to provide a uniform pressure over the width of said area, and means for rockably mounting said frame about an axis parallel to but independent of the mounting of said holder on said frame, said last means enabling said holder to move normal to said fixed plate to vary said area to alter the pressure applied by said plates to said yarn so as to reduce the tension imparted to said yarn by said device to compensate for increase in the pull-off tension to deliver a substantially constant tension yarn to said spool.
